UNITED STATES PATENT OFFICE.

ALFRED COTTON, OF ST. LOUIS, MISSOURI, ASSIGNOR TO HEINE BOILER COMPANY, OF ST. LOUIS, MISSOURI, A CORPORATION OF MISSOURI.

MEANS FOR INTERNALLY SUPPORTING A TUBE THAT IS BEING DEFORMED.

Application filed March 27, 1924. Serial No. 702,280.

This invention relates to sectional headers of the kind that consist of a hollow member constructed from a welded or drawn tube of circular or oval shape in cross section that is deformed by pressure applied externally to the front and rear sides and to the lateral sides of the tube in such a way as to produce a sectional header having alternately-arranged valleys and ridges on its lateral sides and alternately-arranged valleys and ridges on its front and rear sides. Such a header can be produced by arranging a tube between four dies that move inwardly towards the longitudinal axis of the tube and exerting pressure on the tube in such a way as to press opposed portions of the tube inwardly and cause opposed portions of the tube to bulge outwardly, as disclosed in my United States Patent No. 1,565,061, dated December 8, 1925, or it can be produced by a rolling operation, as disclosed in my United States Patent No. 1,565,060, dated December 8, 1925, and my pending application Serial No. 655,666, filed August 4, 1923. If the header is to be provided with hand hole cover seats and tube seats that are produced simultaneously with the operation of forming the inwardly-pressed portions and outwardly-bulged portions on the tube, it is necessary to internally support those portions of the tube that constitute the seat faces during the deforming operation, in order to insure bulged portions of symmetrical shape and seat faces that are sharp-angled and flat.

My present invention consists of a novel means for internally supporting a tube that is deformed in a single operation, or by one continuous operation, so as to produce a header having lateral sides made up of inwardly-pressed portions and outwardly-bulged portions and front and rear sides, each of which is provided with flat surfaces that serve as seats for hand hole covers and for the ends of the tubes to which the header is connected. Due to the fact that the cross-sectional area of a header of the kind above referred to is smaller at all points along its length than the cross-sectional area of the tube from which it is formed, it is not feasible to fill the tube with sand or similar granular material and then deform the tube by pressure applied externally to

the same, because sand is practically incompressible, and consequently, offers so great a resistance to the inward pressure of the dies or rolls that act on the exterior of the tube that the bulges in the tube are liable to be unsymmetrical and the pressing portions on the dies or rolls that form the seat faces of the header are liable to shear through the tube. It is highly desirable, however, to use sand or some other material of a similar nature to internally support a tube that is being deformed to produce a header of the kind above referred to, and accordingly, I propose to fill the tube with a means which is of such a character or nature that during the deforming operation it will collapse transversely of the tube, at numerous points throughout the length of the tube, an amount or degree approximately equal to the difference in volume of the completed header and the tube from which it is constructed. Said means may consist of sand or other suitable granular material that is practically incompressible mixed with an object, objects or a material that will collapse slightly during the deforming operation, or said means may consist of a mass of crushed coke or porous or spongy material, which, when subjected to pressure, will collapse sufficiently to take care of the reduction in volume of the tube as it is formed into a header, and thereafter will become sufficiently resistant to further collapse to insure the deformation of sharp-angled, flat seat faces on the front and rear sides of the header.

In deforming a tube according to my invention the tube can be first filled with the means that is used to internally support the same during the deforming operation, and thereafter arranged in operative position between the external dies or rolls that are used to deform the tube, or the tube can be first arranged in operative relationship with the dies or rolls and said means thereafter introduced into the tube.

Figure 1 is a perspective view of a boiler header produced from a tube that is internally supported during the deforming operation by my improved supporting means.

Figure 2 is a vertical sectional view of said header.

Figure 3 is a vertical sectional view, illustrating a tube arranged in operative posi-

tion between the front and rear dies of a press and filled with a collapsible object and sand or other suitable granular material; and

5 Figures 4 and 5 are vertical sectional views, illustrating other forms of my invention.

While I have herein described my improved supporting means as being used to 10 support a tube that is being deformed to produce a boiler header, it will be understood that it can be used in the manufacture of superheater headers and various other kinds of headers.

15 Referring to the drawings, H designates a sectional header that consists of a hollow member having lateral sides made up of inwardly-pressed portions 1 and outwardly-bulged portions 2, and front and rear sides, 20 each of which is made up of alternately-arranged, inwardly-pressed portions 3 and outwardly-bulged portions 4 that contain flat-faced indentations 5 and 6 that constitute seats for hand hole covers and for the 25 ends of tubes to which the header is connected. Obviously, the shape and area of the indentations 5 and 6 are immaterial. Said header is formed from a tube of oval 30 or circular shape in cross section that is arranged between dies or rolls and then subjected to pressure that is exerted inwardly on said tube from four different directions. The dies or rolls that act on the opposed 35 portions of the tube that constitute the front and rear sides of the header are provided with pressing portions that form the flat seat faces 5 and 6 on the front and rear sides of the header, and during the deforming operation, the portions of the tube in which 40 the indentations 5 and 6 are formed are supported by a means which is capable of collapsing an amount or degree approximately equal to the difference in volume of the tube and the formed header.

45 As previously stated, various means having the above mentioned characteristics can be used for internally supporting the tube during the deforming operation. In Figure 3 of the drawings I have illustrated a tube α arranged in operative position between the front and rear dies A and B of a press 50 of the kind disclosed in my United States Patent No. 1,565,061, dated December 8, 1925, previously referred to, and containing 55 a supporting means composed of a hollow collapsible member C arranged at the center of the tube α and sand or other suitable granular material D arranged between said collapsible member C and the side wall of 60 the tube. When the dies A and B move inwardly into engagement with the tube α , the member C inside of the tube will collapse sufficiently to take care of the reduction in 65 the volume of the tube, as it is formed into a header, and thereafter will become suffi-

ciently resistant to further collapse to cause pressing portions 5^a and 6^a on the dies A and B to form flat-faced, sharp-angled indentations 5 and 6 on the front and rear sides of the tube that will form satisfactory 70 seats for the hand hole covers and the ends of the tubes to which the header is to be connected.

The collapsible member C and granular material D can be placed in the tube α before the tube is arranged in operative position between the dies, or said tube can be first positioned in the dies and the collapsible member and granular material thereafter introduced into the tube. If the tube is to be pressed hot the means that constitutes the internal support for the tube can be arranged inside of the tube before it is heated. Instead of using a single hollow member C to form the collapsible portion of the means that is used to internally support the tube, a plurality of collapsible members may be used. The particular shape of the collapsible member or members is immaterial and it is also immaterial what material is used in the construction of same. 90 When the tube is to be pressed cold a piece of rubber tubing surrounded by a mass of sand or similar granular material can be used to internally support the tube α during the deforming operation, and when the tube 95 is pressed hot, the collapsible member or members that are arranged inside of the tube can be constructed of glass, baked fire clay or a metal that will collapse when subjected to the pressure of the die or rolls used to deform the tube. The essential thing is to fill the tube α with a means that will not collapse during the operation of introducing it into said tube, but which has sufficient 100 collapsibility, when subjected to the pressure of the dies or rolls, to compensate for the difference in volume of the formed header H and the tube α from which the header is constructed.

105 Instead of filling the tube α with a collapsible object or objects surrounded by granular material, as previously described, the tube can be filled with a means consisting of sand or the like and a collapsible material such as coke. If pieces of coke of considerable size are used, say, one-fourth of the bore of the tube α , care should be taken to keep the collapsible material approximately in the center of the tube. This can be easily done by arranging a tubular member inside of the tube that is to be converted into a header, in concentric relation with said tube, then filling said tubular member with coke, then pouring sand or some other suitable material that is practically incom- 115 pressible into the annular space between said tubular member and the side wall of the tube and thereafter withdrawing said tubular member from the tube, thus producing 120 an internal support in the tube composed 125 of sand and coke. The tubular member can be withdrawn from the tube by means of a 130

of a collapsible central portion E of coke surrounded by a mass of sand D, as shown in Figure 4.

It is not essential that the internal supporting means for the tube be formed by a collapsible center core surrounded by a mass of sand or similar granular material that is practically incompressible, for good results can be obtained with an internal supporting 5 means formed by sand intimately mixed with coke crushed to above one-twentieth to one-thirtieth of the diameter of the tube inside of which said means is arranged. Or, if desired, the internal supporting means 10 for the tube can be formed entirely of coke, as shown in Figure 5, wherein the reference character F designates coke crushed to such fineness that it will only collapse sufficiently to take care of the reduction in volume of the tube α as it formed into a header and then become sufficiently resistant to 15 further collapse to cause the external dies or rolls to form sharp-angled, flat-faced seats on the front and rear sides of the 20 header.

It is preferable to start with a tube α provided with a closed lower end and having its upper end portion partly closed, say, to about one-third of the diameter of the original tube, as shown in Figure 3, and make the collapsible member C of such diameter and length that when the lower end of said member rests on the bottom end wall of the tube α , the upper end portion of said member C will project upwardly through the partially closed upper end of the tube without, however, contacting with same, thus leaving an annular space surrounding the upper end portion of the collapsible member 30 C through which sand D can be poured into the tube. While I prefer to start with a tube α having a closed lower end, this is not essential, so long as the tube is of such form that the lower end of the collapsible mem- 35

ber C will bear against same in such a way 45 as to prevent the escape of the granular material D from the lower end of the tube.

In instances where the header is provided with hand hole cover seats and tube seats in close proximity to the upper end of the header, it is necessary that the upper end portion of the tube α be of such shape and dimensions that the sand or other granular material in the tube will not escape through the upper end of the tube during the de- 50 forming operation.

Having thus described my invention, what I claim as new and desire to secure by Letters Patent is:

1. An internal support for a tube that is 60 being deformed so as to produce a header, consisting of a mass of non-compressible, granular material arranged inside of the tube, and a collapsible means extending longitudinally of the tube and surrounded 65 by said non-compressible material, said means being adapted to collapse automatically during the first part of the deforming operation and thereafter becomes sufficiently 70 resistant to further collapse to insure the formation of sharp angled seats faces on the header.

2. An internal support for a tube that is 75 being deformed by dies to convert it into a header provided with flat faces, consisting of a means that completely fills the tube and which comprises a portion that collapses slightly at numerous points throughout the length of the tube during the first 80 part of the deforming operation, due to the inward pressure exerted on the tubes by the dies, and thereafter become sufficiently 85 resistant to further collapse to form a substantially rigid support for parts of the tube that are being shaped to produce sharp angled seat faces on the header.

ALFRED COTTON.
